UNITED STATES PATENT OFFICE

2,499,969

COIN CONTROLLED DISPENSER

Ralph R. Quintrell, Etowah, Tenn.

Application November 13, 1947, Serial No. 785,710

3 Claims. (Cl. 312—47)

1

This invention relates to improvements in coin controlled dispensers.

An object of the invention is to provide an improved coin controlled dispenser which will include a magazine for holding a supply of articles to be delivered one at a time whenever a coin is deposited in the control apparatus.

Another object of the invention is to provide an improved coin controlled dispensing apparatus for dispensing articles one at a time, and for simultaneously replenishing the article holding magazine every time an article is dispensed.

A further object of the invention is to provide an improved coin controlled dispensing apparatus which will be highly efficient in operation, and relatively inexpensive to manufacture and produce.

Other objects will appear as the description proceeds.

In the accompanying drawings which form a part of this application:

Figure 1 is a vertical sectional view through the improved coin controlled dispensing device;

Figure 2 is a sectional view taken on the line 2—2 of Figure 1 the magazine being shown in section;

Figure 3 is a front elevation of the lower portion of the improved coin controlled dispensing device, and

Figure 4 is a perspective view of the article supporting magazine and the replenishing and operating means therefor.

Like characters of reference are used throughout the following specification and the accompanying drawings to designate corresponding parts.

In carrying out the invention, there is provided an upright substantially rectangular case or cabinet generally designated by the reference numeral 1 having four vertical side walls, a bottom 2, and a top 3 hinged at 4 and provided with a securing hasp 5 for receiving a padlock 6.

A transversely extending supporting partition or base 7 is supported upon the angle bracket 8 spaced somewhat above the bottom 2 of the case or cabinet 1, and is formed with a dispensing aperture 9 through which the article 10 to be dispensed will drop when the apparatus is operated.

A chute 11 is supported by the screws 12 below the discharge aperture 9 and angles downwardly, terminating at the discharge opening 13 through the case or cabinet 1, the same being protected by the closure member 14 hinged at 15 to said case or cabinet 1.

2

A door 16 having a lock 17 is provided in the front of the case or cabinet 1 adjacent the closure member 14, whereby when the same is opened, the coins (not shown) which have been collected in the bottom of the case or cabinet 1 may be removed.

An upright substantially rectangular article containing magazine 18 is supported in fixed position in the case or cabinet 1 by means of the bracket 19 attached to the inner wall of said case or cabinet 1. The magazine 18 will comprise parallel compartments 20 and 21 forming a dispensing compartment and a reserve or replenishing compartment respectively. The articles 10 to be dispensed will be placed one upon the other in both compartments 20 and 21, and a spring projected plunger or follower 22 will urge the articles 10 in the reserve compartment upwardly toward the cover 40. An opening 23 will be formed at the top of the compartments 20 and 21 for connecting the same, and for permitting an article 10 to be pushed forwardly from the reserve compartment 21 into the dispensing compartment 20 every time the dispensing device is operated.

A reciprocable operating or actuating plate 24 is slidably supported upon the partition or base 7, and is likewise formed with an article discharge aperture 25 normally in register with the open lower end of the dispensing compartment 20 and disaligned with the dispensing aperture 9 through said base 7.

A vertically extending member 26 is bent in opposite directions at its upper and lower ends 35 to form the refilling or feed plunger arm 27, and supporting plate 28, respectively. A brace 28' is connected between the member 26 and the supporting plate 28 which is fixed to the upper surface of the actuating plate 24.

An ear 29 is bent upwardly at the rear of the plate 24 and is adapted to be engaged by the adjacent end of the operating lever 30 connected with the usual form of coin actuating mechanism generally designated by the reference numeral 31. The lever 30 is slotted as at 32 and receives the guide pin 33 therein which is attached to and supported by the base 7.

In operation, a coin will be placed in the coin actuating mechanism 31 and the lever or plunger 30 will be pushed inwardly to push the plate 24 rearwardly, causing the coin to drop into the bottom of the case or cabinet 1, the apertures 25 with article 10 received therein to be aligned with the aperture 9 through the base 7, and the article 10 dropped into the chute 11 and dis-

pensed. As the lever 30 is retracted the feed arm 27 will force the top article 16 from the reserve compartment 20. Thus, the operation will be repeated as often as a coin is dropped into the coin control mechanism 31.

While the preferred embodiment of the instant invention has been illustrated and described, it will be understood that it is not intended to limit the scope of the invention thereto, as many minor changes in detail of construction may be resorted to without departure from the spirit of the invention.

Having described the invention, what is claimed as new is:

1. A coin controlled dispenser comprising a cabinet, a partition in said cabinet adjacent the bottom thereof having an article discharge aperture therein, a chute carried by said partition below said aperture, a magazine supported in said cabinet above said partition, said magazine comprising parallel article dispensing and reserve compartments, a resiliently projected follower in said reserve compartment normally urging an article in said compartment towards the top thereof, a coin receiving and actuating plate slidable on said partition having an article receiving aperture, and an article engaging finger

laterally movable in said reserve compartment simultaneously with the rectilinear reciprocation of the actuating plate, said finger being a horizontal lug, and means for securing said lug to said actuating plate.

2. The combination of claim 1 wherein said means includes a vertically extending member terminally secured to said lug and said actuating plate.

3. The combination of claim 2 wherein said member is L-shaped and includes an inclined brace member interconnecting the leg portions of said member.

RALPH R. QUINTRELL.
